UNITED STATES PATENT OFFICE.

HENRY S. PUTNAM, OF NEW YORK, N. Y., ASSIGNOR TO CONTINUOUS TRANSIT COMPANY, OF NEW YORK, N. Y., A CORPORATION OF DELAWARE.

TRUCK CONSTRUCTION FOR MOVING PLATFORMS.

Application filed June 22, 1923. Serial No. 647,136.

To all whom it may concern:

Be it known that I, HENRY S. PUTNAM, a citizen of the United States, a resident of 118 E. 54th St., New York, in the county of New York and State of New York, have invented a certain new and useful Truck Construction for Moving Platforms, of which the following is a specification.

The invention relates to trucks or cars adapted to be coupled together to make up a train or moving platform, and particularly to trains or moving platforms which are propelled by means of driving elements disposed along a trackway and cooperating with complementary driving elements disposed on the trucks to actuate the latter. Such a moving platform is described, for example, in prior Patents Nos. 1,437,549 and 1,437,550, both issued to me on December 5th, 1922.

The primary object of the invention is to so construct trucks of the above nature that their driving elements may be brought into the exact position relative to the complementary driving elements disposed along the track which is necessary to insure that the above elements will cooperate properly to propel the train or platform. In certain of its aspects the invention is applicable to both mechanical and electrical drives for platforms as above described, while certain other features of the embodiment of the invention hereinafter described, are designed more particularly for mechanical drives.

Further objects and advantages of the invention will be in part obvious and in part specifically pointed out in the description hereinafter contained, which, taken in connection with the accompanying drawings, discloses a preferred embodiment of the invention; such embodiment, however, is to be considered merely as illustrative of its principles. In the drawings:

Fig. 1 is a plan view illustrating a truck constructed in accordance with the invention.

Fig. 2 is a central vertical section of the structure shown in Fig. 1.

Fig. 3 is a section on line 3—3 of Fig. 1, looking in the direction of the arrows.

Fig. 4 is a fragmentary plan view showing coupling devices for connecting the trucks into a train or endless platform.

Fig. 5 is a diagrammatic plan view of an

endless platform made up of trucks, in accordance with the invention. 55

Fig. 6 is a side view of certain of the trucks which appear in Fig. 5, and their cooperating driving elements.

The truck shown in the illustrated embodiment of the invention is a body made up of longitudinal supporting members 1, which are connected together by means of cross pieces 2. All of the above members will usually consist of beams of standard structural shapes. In the present instance each truck is provided with but one axle 3, carrying wheels 4, and the forward end of each truck is pivotally supported by the rear end of the truck next preceding, as is described in general in my prior United States patents above-mentioned. The forward end of each truck is provided with a draw bar 5 supported by one of the cross pieces 2, and having a hole 6 adapted to receive a king pin 7. This king pin also extends through a trunnion member 8, which is shown as a plate having transversely extending hubs 9 which are received between ears 10 on the rear axle 3 of the truck next preceding. Thus each truck is provided near each of its opposite ends with an element of a pivotal connection, thereby permitting the trucks to move angularly with regard to each other when passing around curves; also the trunnion members 8 being slidably and pivotally engaged with the ears 10, permit the trucks to shift vertically as may be necessary to enable the platform to accommodate itself to changes in grade. 70 75 80 85 90

The trucks are provided with driving elements 11 extending lengthwise thereof and adapted to cooperate with complementary driving elements disposed along the trackway to drive the trucks, and these driving elements may be of various types. In some instances an electric drive may be employed consisting of primary coils of the induction motor type disposed along the track, in which case the driving elements 5 will be in the form of short-circuited secondaries, all as is described in greater detail in my prior patents above referred to; in other instances a mechanical drive may be employed, in which case the driving elements 5 may take the form of racks, engaging driving pinions or gears disposed along the 95 100 105

trackway, or friction rails engaging friction wheels disposed along the trackway.

In accordance with the present invention, the trucks are so constructed that the spacing between the ends of the driving elements 11 upon adjacent trucks, may be altered. This is accomplished in the illustrated embodiment of the invention by so supporting the draw bar members 5 from the bodies of 10 the trucks that the distance between the pivot points of the trucks may be altered; as shown, the draw bar 5 is clamped to one of the cross pieces 2 by means of bolts 12 and one or more spacing devices 13, which 15 may be merely flat sheets or plates, is interposed between the draw bar 5 and cross piece 2. Thus if the driving elements 11 are racks driven by pinions disposed along the trackway, the spacing between adjacent 20 racks 11 may be obtained which will bring the teeth on the racks into phase with each other, whereby the driving pinion will pass from one rack to the next succeeding, without a jerky or improper engagement which 25 would injure or strain the parts. Where the trucks are assembled in an endless moving platform, the above construction also enables the effective lengths of the trucks to be adjusted to correspond to the perimeter 30 of the track.

The driving elements 11 are also supported by the body of the truck in such manner that the elevation with respect to the trackway can be altered as may be desired. In 35 the present instance the driving elements 11 are clamped to the bottoms of the cross pieces 2 and rear axle 3 of each truck, by means of bolts 14, and spacing devices 15, which may be similar to the parts 13 above- 40 described, are interposed between the driving elements and their respective supports. Thus, if racks are employed as driving elements 11, the rack of each truck may be so positioned as to bring its teeth into proper 45 engagement with the teeth on the driving pinion, the spacing devices 15 being employed to such extent that the driving element 11 is located parallel to the trackway, and at the desired height above the same. 50 If an electric drive is used as above mentioned, the above features are also desirable, since the efficiency of such a drive is dependent upon the accurate maintenance of a proper air gap between the secondaries 55 on the trucks, and the primaries located along the track, and also to compensate for wear of the wheels and rails.

The invention also comprises a moving platform made up of a series of trucks of 60 the nature above-described, and connected together to form a continuous loop, as is illustrated in Fig. 5, and driven by means of racks carried by the respective trucks, engaging with pinions or gears disposed at 65 intervals along the trackway. As is shown

in Fig. 6, the racks 11 may be driven by pinions or gears 16 which in turn are driven by chains 17 from electric motors 18.

While a specific embodiment of the invention has been disclosed, it will be obvious 70 that many changes may be made therein without departing from its spirit, as defined in the following claims.

I claim:

1. In combination a series of trucks disposed end to end, aligned racks extending respectively along the several trucks and adapted to cooperate with driving elements disposed along a trackway to propel the trucks, and means for altering the spacing 75 between the ends of adjacent racks to bring the teeth of the racks into phase with each other.

2. In combination a series of trucks disposed end to end, coupling devices near the ends of adjacent trucks to interconnect the same, aligned racks extending respectively along the several trucks adapted to cooperate with driving elements disposed along a trackway to propel the trucks, and means 80 associated with said coupling devices for altering the spacing between the ends of adjacent racks to bring the teeth of the racks 85 into phase with each other.

3. A truck construction comprising body 90 members with wheels adapted to guide the truck along a track, a rack extending lengthwise of the truck and adapted to cooperate with driving elements disposed along the trackway to propel the truck, an element of 95 a pivotal connection disposed near each of the opposite ends of said truck, and means for altering the distance between the pivot points of the last-mentioned elements.

4. A truck construction comprising body 100 members with wheels adapted to guide the truck along a track, a rack extending lengthwise of the truck and adapted to cooperate with driving elements disposed along the trackway to propel the truck, coupling devices disposed near the opposite ends of the truck, means for clamping one of said coupling devices to the body of the truck, and a removable spacing device interposed between 105 said last-mentioned coupling device and the 110 body of the truck.

5. A truck construction comprising body 115 members with wheels adapted to guide the truck along a track, a driving element carried by the truck extending lengthwise 120 thereof and adapted to cooperate with complementary elements disposed along the trackway to drive the truck, means being provided to alter the elevation of said driving element with respect to the trackway. 125

6. A truck construction comprising body 130 members with wheels adapted to guide the truck along a track, a driving element carried by the truck extending lengthwise thereof and adapted to cooperate with com-

plementary elements disposed along the trackway to drive the truck, and means disposed at points spaced along the length of the truck for altering the elevation of the 5 driving element with respect to the trackway.

7. A truck construction including a body having longitudinal supporting members, cross pieces extending therebetween, a driving 10 element for the truck extending lengthwise thereof beneath said cross pieces and adapted to cooperate with complementary elements disposed along the trackway to propel the truck, and means for supporting 15 said driving element from said cross pieces, said means permitting alteration of elevation at which said driving element is supported with respect to the trackway.

8. A truck construction including a body 20 having longitudinal supporting members, cross pieces extending therebetween, a driving element for the truck extending lengthwise thereof beneath said cross pieces and adapted to cooperate with complementary 25 elements disposed along the track, to propel the truck, means for clamping said driving element to said cross pieces and removable spacing devices interposed between said driving element and said cross pieces.

30 9. A truck construction comprising body members with wheels adapted to guide the truck along a track, a driving element extending lengthwise of the truck and adapted to cooperate with complementary elements 35 disposed along the trackway to propel the truck, means for altering the position of said driving elements with respect to the

trackway, and means for altering the distance between the pivotal connection elements. 40

10. An endless platform comprising a series of trucks pivotally connected together to make up a continuous loop, each of said trucks having wheels at one end only, and mechanism for connecting the remaining 45 end of each truck to the wheeled end of an adjacent truck, said trucks carrying racks extending respectively along the same, and pinions disposed at intervals along the trackway and meshing with said racks to propel 50 the same.

11. An endless platform comprising a series of trucks pivotally connected together to make up a continuous loop, said trucks carrying racks extending respectively along 55 the same, pinions disposed at intervals along the trackway and meshing with said racks to propel the platform, and means for altering the spacing between the ends of adjacent racks to bring the teeth of the racks into 60 phase with each other.

12. An endless platform comprising a series of trucks pivotally connected together to make up a continuous loop, said trucks carrying racks extending respectively along 65 the same, pinions disposed at intervals along the trackway and meshing with said racks to propel the platform, and means being provided to alter the elevation of said racks with respect to the trackway. 70

In testimony that I claim the foregoing, I have hereunto set my hand this 18th day of June, 1923.

HENRY S. PUTNAM.
